J. W. GOODERHAM

TELEPHONE EXCHANGE SYSTEM

Filed July 28, 1921

Inventor:
John W. Gooderham
by E.R. Nowlan Atty.

UNITED STATES PATENT OFFICE.

JOHN W. GOODERHAM, OF YONKERS, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed July 28, 1921. Serial No. 488,075.

To all whom it may concern:

Be it known that I, JOHN W. GOODERHAM, a citizen of the United States, residing at Yonkers, in the county of Westchester, State 5 of New York, have invented certain new and useful Improvements in Telephone-Exchange Systems, of which the following is a full, clear, concise, and exact description.

This invention relates to a telephone exchange system, and more particularly, to a system in which means are provided for charging calling subscribers with all successful calls which they initiate.

In telephone exchange systems in which 15 connections between subscribers' lines are established by means of automatic switching mechanism and in which each subscriber's line is provided with but a single substation, it is possible to charge calls upon calling subscriber's individual message registers with no great difficulty. When, however, a subscriber's line is provided with a plurality of substations, as is the usual practice on 20 party lines, it then becomes necessary to associate a plurality of message registers with each party line, the registers being individual respectively to the several substations on the line and to select before registration, the register individual to the calling party 25 on the line.

One method of accomplishing this desirable result has been disclosed in the application of D. M. Taggart and F. J. Scudder, Serial No. 431,141, filed December 16, 1920. 35 In this aforementioned application the principle of party line message registration was disclosed as applied to party lines having two substations each. The present invention has been developed to provide for message 40 registration on party lines having any desired number of substations. It is, therefore, an object of this invention to provide simple and improved means for message registration on subscribers' lines having a 45 plurality of substations.

It is a further object of the invention to provide means for detecting which one of a plurality of individual or branch circuits is connected at any time to a common circuit.

The invention resides broadly in providing each branch of a common circuit with a 50 tuned circuit acting as a filter to pass alternating current of all but a certain frequency, the filters associated with the several 55 branches being differently tuned; in asso-

ciating a responsive device with the common circuit and in providing a plurality of alternating current sources of different frequencies which are adapted to be associated with the common circuit in succession. Thus, if 60 a certain branch of the common circuit be closed and current from the several sources be successively applied, the responsive devices will respond upon the application of each source of current to the common circuit, 65 except upon the application of the source having a frequency to which the filter of the particular branch is anti-resonant. If another branch having a differently tuned filter be closed, the responsive device will, therefore, function in a different manner. Therefore, by the provision of suitable mechanism associated with the responsive device a registration of the particular branch of the common circuit, which has been closed, may be 70 75 made for any desired purpose as, for example, for message registration as herein illustrated.

It is believed that the invention may be 80 more readily understood from a consideration of the following description taken in connection with the figure of the accompanying drawing. The drawing discloses a calling subscriber's line provided with four substations and terminating in the wipers of a 85 line switch individual thereto. The line switch has access to a district link circuit of the well-known type, such as disclosed in the Patent No. 1,395,977 issued to F. A. Stearn and F. J. Scudder, November 1, 1921. Since 90 the invention is not directly concerned with the circuits of this district selector, only such portions thereof as are necessary to an understanding of the invention have been disclosed. Associated with the district selector is an office sender designated by the small rectangle in the lower left-hand corner of the figure. This office sender may be of the type disclosed in the aforementioned patent to F. A. Stearn and F. J. Scudder. 95 For further extending the connection to the line of a desired called subscriber, an incoming selector and a final selector may be employed. These selectors have been designated on the drawing by a representation of 100 their respective brushes.

For associating sources of alternating current of different frequencies with the calling subscriber's line to determine the particular substation calling, a step-by-step ro- 110

5 tary switch of the well-known type is employed. The thermionic relay designated by the numeral 57 is employed in the testing circuit as a means for determining which 10 current frequencies find a path over the calling line and thereby determines the selection of a message register corresponding to the particular substation calling. This 15 thermionic relay is of the well-known audion type and needs no further description herein.

In the present disclosure the calling line is shown equipped with four substations, 1 to 4 inclusive, each substation being equipped 20 with a band filter designated as 5, 6, 7 and 8, respectively. The band filter of each substation comprises an impedance coil and a condenser designated, for example, at 25 substation No. 1 as 9 and 10. The filter of substation No. 1 is so tuned as to be resonant to one particular frequency of current, the band filter 6 at substation No. 2 being resonant to a certain other frequency and the band filters 7 and 8 and substations 3 30 and 4 being also resonant to other frequencies. Thus, when alternating current of four different frequencies is impressed upon the calling line, if at the time the receiver of substation No. 1 is off its switchhook, current of three of the frequencies will 35 pass readily through the filter 5, but the fourth frequency will not pass therethrough since the filter is resonant to such fourth frequency.

35 It will be assumed that the subscriber at substation No. 1 on the calling line initiates a call by the removal of his receiver from its switchhook for the purpose of obtaining a connection with the line of the called subscriber 38. Upon the removal of the receiver from the switchhook, a circuit is established over the line conductors 11 and 12 in the well-known manner, thereby causing the 40 positioning of the wipers 13 and 14 of the subscriber's individual line switch upon the terminals 15 and 16 of a district link circuit which terminates in the district selector brushes 24 and 25. Upon the extension of the calling line to the district link, a 45 circuit is established in the well-known manner for the sequence switch magnet 17 for advancing the sequence switch of the district selector out of its normal position into position 3, in which latter position the office sender 18 is associated with the calling subscriber's line over conductors 22 and 23 and the upper left contacts of cams 20 and 21. The calling subscriber thereupon proceeds 50 to operate his sending dial 19 to set the registers of the sender 18 in accordance with the office and line designation of the desired line. In accordance with the registration set up upon the office sender the brushes 24 and 25 of the district selector are positioned in the well-known manner

50 upon terminals 26 and 27 of a trunk circuit extending to an incoming selector switch represented by the brushes 32 and 33. The sequence switch 17 is now advanced to position 11 and the office sender thereupon functions to control the setting of the brushes 32 and 33 of the incoming selector and the brushes 34 and 35 of a final selector upon the terminals 36 and 37 of the desired line 55 70 75 80 85 90 95 100 105 110 115 120 125 130 135 140 145 150 155 160 165 170 175 180 185 190 195 200 205 210 215 220 225 230 235 240 lay 57, the input circuit of the relay comprising the upper winding of transformer 51, the filament 58 and the grid 59. As a result of the current flowing in the input circuit of the thermionic relay, current is caused to flow in the output circuit of the relay from the positive pole of battery through the left winding of relay 60, the plate 61, thence to the filament 58 and to ground. Relay 60 energizes in response to the current flowing through its winding and closes a circuit for relay 63 which may be traced from battery through the winding of relay 63, bank terminal 62, wiper 47, and thence to ground through the armature contact of relay 60.

In a similar manner as the wiper 48 advances to its third position bank terminal, the source of current 55 is inductively connected to the test circuit and the thermionic relay 57 again responds, establishing a circuit for the relay 65. When the wiper 48 engages its No. 4 contact, the source of current 56 is inductively associated with the test circuit and causes the energization of relay 66. Relays 63, 65 and 66, upon energizing, close locking circuits for themselves extending over their right armature contacts and conductor 64 to ground at the lower left contact of cam 42. When the register selector advances its wipers to such a position that wiper 45 engages bank terminal 96, the register selector is arrested and awaits restoration which is accomplished when the calling subscriber releases the connection upon the termination of the conversation. It is to be noted that three relays 63, 65 and 66 have now been locked energized for preparing a circuit for the register corresponding to the calling substation No. 1.

With sequence switch 17 in position 13, polarized relay 41 energizes as soon as the called subscriber 38 responds to the call. The circuit of relay 41 may be traced in part over the contact of cam 39, the left contact of cam 30, brush 24, bank terminal 26 and returning over terminal 27, brush 25, the left contact of cam 31 and thence over the contact of cam 40, current for operating relay 41 being supplied from the link circuit associated with the incoming selector in the well-known manner. Upon the energization of relay 41 a circuit is established for relay 68 which becomes effective as soon as cam 70 rotates to such a position as to close its contact springs 69. This circuit may be traced from battery through the contact springs 69, the winding of relay 68, conductor 67, the armature contact of relay 41 and to ground over the upper left contact of cam 42. Relay 68, upon energizing, locks through its right-hand armature contact independent of cam springs 69 and at its left armature contact prepares a circuit for relay 71 which is effective as soon as cam

70 rotates to such a position as to close contact springs 72. Relay 71, upon energizing, locks over its right armature contact and the contact of cam 73, and at its left-hand armature contact prepares an operating circuit for the selected message register.

Upon the termination of the conversation and the restoration of the calling subscriber's receiver to its switchhook, the supervisory relay 74 deenergizes, closing a circuit for advancing the sequence switch 17 of the district link out of its talking position into position 17 in the manner set forth in the aforesaid patent to F. A. Stearn and F. J. Scudder. With sequence switch 17 in position 17 the operating circuit of the selected message register is established, which may be traced from battery through the contact of cam 81, the left armature and contact of relay 71, conductor 80, the left armature and front contact of relay 66, the inner left armatures and front contacts of relays 65 and 63, the inner left armature and back contact of relay 82, conductor 79, bank terminal 78 and wiper 77 of the subscriber's line switch and to ground through the winding 76 of the message register which is individual to substation No. 1. A circuit is also closed at this time from ground through the upper right-hand contact of cam 42, conductor 75, bank terminal 96, wiper 45 and through the winding of stepping magnet 46 for advancing the register selector into its normal position. Following message registration, the district selector and the other switches employed in the establishment of the connection are restored in the well-known manner.

Had the calling substation No. 2 initiated the call, then since the filter 6 associated with such substation is resonant to current of the frequency generated by the source 54, current would flow over the testing circuit 52, 53, only when the sources 49, 55 and 56 are associated therewith, and consequently, through the operation of the thermionic relay 57, locking relays 82, 65 and 66 would be operated. Thus when the sequence switch 17 reaches position 17 for registering a successful call, the message register 86 individual to the substation 2 would be operated over a circuit extending from battery through the contact of cam 81, the left armature and contact of relay 71, conductor 80, the left armature and front contact of relay 66, the inner left armature and front contact of relay 65, the inner left armature and back contact of relay 63, armature contact 97 of relay 82, conductor 83, terminal 84, wiper 85, and thence to ground through the winding of register magnet 86. In a similar manner if substation No. 3 initiates a call the thermionic relay 57 responds only when current from sources 49, 54 and 56 is applied to the testing circuit, and consequently, re-

lays 66, 63 and 82 are operated. With relays 66, 63 and 82 operated, the message register 90 is selected for operation. If the station No. 4 initiates the call, thermionic relay 57 responds only when current from the sources 49, 54 and 55 is applied to the test circuit 52, 53, in which case, relays 82, 63 and 65 operate to prepare a circuit for the message register 94.

10 When two subscribers on the same line attempt to call simultaneously or have their receivers off their switchhooks at the time the registration test is made, all four relays 63, 65, 66 and 82 will become energized and 15 no operating circuit for message registers is effective. Such operated condition of all of these relays might be employed to operate an alarm signal by connecting such a signal 86 to the inner front contact of relay 82.

20 While the invention has been disclosed in connection with a subscriber's line having four substations, it is obvious that it is 25 equally applicable to lines having more than four substations, it only being necessary to equip the additional substations with tuned circuits differing from the tuned circuits supplied for the other substations and to provide additional sources of current, locking relays and message registers at the central office. Further, it is apparent that the 30 invention is not necessarily limited in its application to message registration, as the principles involved in the invention might be applied to any circuit problem where it 35 would be desirable to determine which of a plurality of branch circuits is at any time connected to a main or common circuit, and in the appended claims this broader interpretation of the invention should be borne in mind.

What is claimed is:

1. In combination with a main circuit and a plurality of normally open branches therefor, of an electrically selective device associated with each of said branches, said several devices differing from each other in their selectivity, means associated with each of said branches for effecting its closure, a plurality of sources of current of different characteristics, means for associating said sources in succession with said main circuit, and means selectively responsive to the flow of said electric currents through said selective device for determining which of said branches is closed.

2. In combination with a main circuit and a plurality of normally open branches therefor, of a frequency selective device associated with each of said branches, said several devices differing from each other in their selectivity, means associated with each of said branches for effecting its closure, means for successively applying electric currents of different frequencies to said main circuit, and means selectively responsive to the flow

of said electric currents through said selective devices for determining which of said branches is closed.

3. In combination with a main circuit and a plurality of normally open branches therefor, of a filter associated with each of said branches, said several filters being tuned respectively to be selective to currents of different frequencies, means associated with each of said branches for effecting its closure, means for successively applying electric currents of different frequencies to said main circuit, and means selectively responsive to the flow of said electric currents through said filters for determining which of said branches is closed.

4. In combination with a main circuit and a plurality of normally open branches therefor, of a filter associated with each of said branches, said several filters being tuned respectively to be resonant to currents of different frequencies, means associated with each of said branches for effecting its closure, means for applying electric currents of different frequencies in succession to said main circuit, and means selectively responsive to the flow of said electric currents through said filters for determining which of said branches is closed.

5. In a signaling system, a main circuit, a plurality of normally open branches therefor, a frequency selective device associated with each of said branches, said several devices differing from each other in their selectivity, means associated with each of said branches for effecting its closure, means for applying electric currents of different frequencies in succession to said main circuit, a thermionic relay associated with said main circuit responsive to the currents flowing thereover through said selective devices and signaling means controlled by said relay for indicating which of said branches is closed.

6. In a signaling system, a main circuit, a plurality of normally open branches therefor, a filter associated with each of said branches, said several filters being tuned respectively to be anti-resonant to currents of different frequencies, means associated with each of said branches for effecting its closure, means for applying electric currents of different frequencies in succession to said main circuit, a thermionic relay associated with said main circuit responsive to the currents flowing thereover through said filters and signaling means controlled by said relay for indicating which of said branches is closed.

7. In a signaling system, a main circuit, a plurality of normally open branches therefor, a filter associated with each of said branches, said several filters being tuned respectively to be resonant to currents of different frequencies, means associated with

- each of said branches for effecting its closure, means for applying electric currents of different frequencies in succession to said main circuit, a thermionic relay associated 5 with said main circuit and operated by current flowing thereover from any of said sources, a plurality of relays, means for associating said relays in succession for operation by said thermionic relay and signaling means selectively operable under the control of said relays for indicating which of said branches is closed.
8. In a signaling system, a main circuit, a plurality of normally open branches therefor, a filter associated with each of said branches, said several filters being tuned respectively to be resonant to current of different frequencies, means associated with each of said branches for effecting its closure, sources of current of the frequencies to which said filters are resonant, a thermionic relay associated with said main circuit and operated by current flowing thereover through any one of said filters 20 from any of said sources, a plurality of relays controlled by said thermionic relay, a switching device for successively associating said sources of current with said main circuit and said relays with said thermionic relay and signaling means selectively operable under the control of said relays for indicating which of said branches is closed.
9. In a signaling system, a main circuit, a plurality of normally open branches therefor, a filter associated with each of said branches, said several filters being tuned respectively to be resonant to current of different frequencies, means associated with each of said branches for effecting its closure, sources of current of the frequencies to which said filters are resonant, a thermionic relay associated with said main circuit and operated by current flowing thereover through any closed branch thereof from 35 such of said sources of current as are in the resonance range of the filter of said closed branch, a plurality of relays controlled by said thermionic relay, a switching device for successively associating said sources of current with said main circuit and said relays with said thermionic relay and signaling means selectively operable under the control of said relays for indicating which of said branches is closed.
10. In a signaling system, a main circuit, a plurality of normally open branches therefor, a filter associated with each of said branches, said several filters being tuned respectively to be resonant to current of different frequencies, means associated with each of said branches for effecting its closure, sources of current of the frequencies to which said filters are resonant, a thermionic relay associated with said main circuit and operated by current flowing over 40 45 50 55 60 65
- said main circuit through any closed branch thereof from such of said sources of current as are in the resonance range of the filter of said closed branch, a plurality of relays controlled by said thermionic relay, a switching device for successively associating said sources of current with said main circuit and said relays with said thermionic relay, and a plurality of signaling devices selectively operable under the control of 70 75 80 85 90 95 100 105 110 115 120 125 130 said relays for indicating which of said branches is closed.
11. In a telephone system, a subscriber's line, a plurality of normally open substation branches thereon, an electrical selective device associated with each of said branches, said several devices differing from each other in their selectivity, means at each substation for effecting the closure of its branch, a plurality of sources of current of different characteristics, means for associating said sources in succession with said subscriber's line, and means responsive to the flow of said electric currents through said selective devices for registering which of said substation branches is closed.
12. In a telephone system, a subscriber's line, a plurality of normally open substation branches thereon, a filter associated with each of said branches, said several filters being tuned respectively to be resonant to current of different frequencies, means at each substation for effecting the closure of its branch, means for applying electric currents of different frequencies in succession to said subscriber's line, and means responsive to the flow of said electric currents through said filters for registering which of said substation branches is closed.
13. In a telephone system, a subscriber's line, a plurality of normally open substation branches thereon, a filter associated with each of said branches, said several filters being tuned respectively to be resonant to currents of different frequencies, means at each substation for effecting the closure of its branch, means for applying electric currents of different frequencies in succession to said subscriber's line, a thermionic relay adapted to be associated with said subscriber's line responsive to the currents flowing thereover through said filters, and a plurality of message registers individual respectively to said substation branches selectively controlled by said relay for registering which of said branches is closed to initiate a call.
14. In a telephone system, a subscriber's line, a plurality of normally open substation branches thereon, a filter associated with each of said branches, said several filters being tuned respectively to be resonant to currents of different frequencies, means at each substation for effecting the closure of its branch, means for applying electric 120 125 130

- currents of different frequencies in succession to said subscriber's line, a thermionic relay adapted for association with said subscriber's line and to be operated by current flowing over said line from any of said sources, a plurality of relays controlled by said thermionic relay, means for associating said relays successively with said thermionic relay, and a plurality of message registers individual respectively to said substation branches and operable under control of said relays for registering which of said branches is closed to initiate a call.
15. In a telephone system a subscriber's line, a plurality of normally open substation branches thereon, a filter associated with each of said branches, said several filters being tuned respectively to be resonant to current of different frequencies, means at each substation for effecting the closure of its branch, sources of current of the frequencies to which said filters are resonant, a thermionic relay associated with said subscriber's line and operated by current flowing thereover through any closed substation branch thereof from such of said sources of current as are in the resonance range of the filter of said closed branch, a plurality of relays controlled by said thermionic relay,

and a plurality of message registers individual respectively to said substation branches selectively operable under the control of said relays for registering which of said branches is closed to initiate a call. 35

16. In a telephone system, a subscriber's line, a plurality of normally open substation branches thereon, a filter associated with each of said branches, said several filters being tuned respectively to be resonant to currents of different frequencies, means at each substation for effecting the closure of its branch, means for applying electric currents of different frequencies in succession to said subscriber's line, a thermionic relay adapted to be associated with said line and operated by current flowing thereover from any of said sources, a plurality of relays controlled by said thermionic relay, means for associating said relays successively with said thermionic relay, a plurality of message registers individual respectively to said substation branches and selectively under the control of said relays in accordance with the particular substation branch which has been closed to initiate a call, and means effective upon the termination of a connection for operating the selected message register. 40 45 50 55 60

In witness whereof, I hereunto subscribe my name this 23rd day of July, A. D., 1921.

JOHN W. GOODERHAM.
